C. E. Smith,

Brad Setter

No. 24,520.

Patented Sep. 7, 1869.

CHARLES E. SMITH, OF COLUMBUS, OHIO.

Letters Patent No. 94,520, dated September 7, 1869.

IMPROVEMENT IN BRAD-SETTER.

The Schedule referred to in these Letters Patent and making part of the same.

To all whom it may concern:

Be it known that I, CHARLES E. SMITH, of Columbus, in the county of Franklin, and State of Ohio, have invented an Improved Brad-Setter, for glaziers' use; and I do hereby declare that the following, taken in connection with the drawings, which accompany and form part of this specification, is a description of my invention, sufficient to enable those skilled in the art to practise it.

My invention consists in a removable case or magazine, for holding in proper position a large number of glaziers' "brads" or "points," for feeding them automatically, one by one, as wanted, and in a locking-device, to hold to place the removable case or cartridge, when supplied with its load of "brads," and which also allows of the ready removal of the case when emptied, that its place may be supplied with another filled case.

In the accompanying drawings—

Figure 1 represents a side view of my novel implement, ready for use.

Figure 2 is a central vertical section, the brads being in position for the lowest one to be pressed forward into the sash.

Figure 3 is a similar section, such brad having been forced forward.

Figure 4 is a top view of the bed-plate, in which the shover or forcing-plate, connected with the handle, reciprocates, and of a vertical tube thereon, and its enclosed spring-follower.

Figure 5 represents one of the brads.

Figure 6 represents one of the cases or magazines filled, ready to be substituted for an empty one, and having covers for each end, to keep the contents in proper place, until the case is to be applied to the other apparatus.

A is the handle, which, with its stem B, is placed at a proper angle with the flat portion C of the stem, so as to permit the bed-plate to be placed flat upon the pane of glass, without cramping the hand between the handle and the glass.

This portion C is arranged to slide lengthwise in appropriate ways, in the bottom of the bed-plate D, and is about flush with such bottom.

It has at its forward end a thin plate or pusher, E, of about sufficient thickness to insure its front straight edge coming against the rear straight edge of the lowermost "point," that it may push it forward, all which is plainly shown in figs. 2 and 3, the bed-plate having on its under side, at its forward end, a thin plate, F, flush with the rear part of the under side, as shown in fig. 7, leaving an open space, G, between them, to allow the play of the pusher and the discharge of the brad, when forced against and into the sash.

H is a short tube, secured to the flat part C, closed

at its rear end and open at its front end, and containing a coiled or other spring, as shown.

The under side of this tube is slotted, to allow the neck of the piece I or plate D to ride therein.

When the handle is pressed forward to drive a brad, it compresses the spring against I, and when the pressure is withdrawn, the spring returns or restores the handle to its former or normal position.

A slot, K, in plate D, in connection with a headed pin or screw, L, in the part C of the handle, serves not only to limit properly the range of reciprocating motion of the pusher, but also to keep the parts together, and to aid in guiding the movements.

M is a vertical tube, open at one side, erected on the bed-plate D, and within which is a coiled or other spring, attached to a triangular-shaped pressing-cap or follower, N, the neck of which rides in the slit or opening O in the front side of the tube M, the follower being shaped and applied so that when the machine is ready for use, it shall exert a constant and steady pressure upon the pile of brads within the triangular magazine-case P, which has also a longitudinal slit in one side, as shown best in fig. 6, to allow the neck of the follower N to ride freely therein.

Q is a triangular socket on the bed-plate, to receive one end of case P, and hold it to its place at the bottom, and

R is a locking-piece, formed of about one-third of a tube in longitudinal section, and having a cap thereon, within which is a pin, S, to enter an irregular slot or groove, somewhat like a bayonet-groove, to enable the piece R to be applied, turned, and so locked to the tube M, the long portion R' of such locking-piece at its lower end abutting against the top of the case P, and holding it down to place.

The operation will be readily understood from the above description.

The case P, supplied with a number of brads, being secured to place as stated, the operator, holding the handle A in one hand, has but to apply the front or discharging-end of the plate to the place on the sash where the brad is to be driven, and press forward the handle, to drive the brad into the wood. The handle, by force of the spring in tube H, returns to its place. The spring in tube M immediately advances the next brad to the proper position to be similarly driven, and the operation may be repeated as expeditiously as possible.

The pressure of spring T on the follower is made sufficient to keep the brads flat upon each other, and in proper condition for successful working of the apparatus, in whatever position it may be held, so that no derangement follows from driving a brad upward, downward, or to either side of the sash.

It is evident that mere formal changes or altera-

tions in some or most of the details of construction may be made without departing from the spirit of my invention.

I claim—

1. A case, for carrying a stock of glaziers' "brads" or "points," constructed so as to be attachable and removable from the brad-driving apparatus, substantially as and for the purpose set forth.

2. The combination of the removable case P, the tube M and its pressing-devices, and the locking-piece R, substantially as shown and set forth.

CHAS. E. SMITH.
